UNITED STATES PATENT OFFICE

EDWARD B. HESS, OF ORLANDO, FLORIDA, ASSIGNOR TO ROYAL TYPEWRITER COMPANY, INC., OF NEW YORK, N. Y., A CORPORATION OF NEW YORK

TYPEWRITING MACHINE

Application filed September 18, 1928. Serial No. 306,676.

An object of this invention is to provide a new and improved type action for typewriting and similar machines which is simple in construction, rapid and efficient in operation, will eliminate substantially all of the noise which results from the operation of the usual type action in present commercial machines, and at the same time will provide visible writing.

10 The type action, which is hereinafter more specifically described, consists of a plurality of type carriers which are mounted in a segment to normally hang downwardly by gravity in a vertical position. These carriers are adapted to be swung to an operative printing position in front of the platen by connections with the usual key levers. Each type carrier has mounted on the free end thereof a slideable type block which is yieldably held against movement relative to the carrier. The connection between each type carrier and its associated key lever embodies a loose connection whereby the carrier may be swung to its operative printing position during the first part of the depression of said key lever and whereby said key lever may be further depressed as a result of said loose connection to actuate a single impression member for moving the type block relative to the carrier and against the tension of the spring to permit said block to perform its printing operations.

25

30

A further object of the invention lies in the provision of a type action such as specified above which may be substituted in a typewriting machine without substantial modification of the other instrumentalities. The invention is illustrated as applied to a standard Royal typewriting machine in which this action has been embodied with but little change in the construction of the other instrumentalities of the machine, such as the key board, the carriage, the platen shift mechanism, ribbon mechanism, escapement mechanism, and the like. Therefore certain of these instrumentalities have been purposely omitted from the drawings, as such instrumentalities have no direct bearing on this particular invention.

40

45

50

Other objects of the invention will be ap-

parent from the following detailed description and will be set forth in the appended claims.

In the drawings:

Figure 1 is a top plan view of a typewriting machine embodying my invention;

Figure 2 is a view showing in perspective the various parts of type arm and type block assembly;

Figure 3 is a transverse sectional view of the machine showing the parts in their normal positions;

Figure 4 is a similar view but showing one of the type carriers in its operative or printing position and the associated key lever as being partially depressed;

Figure 5 is a view similar to Figure 4 but showing the impression member in its effective working position, the type block in printing position, and the associated key lever in its fully depressed position;

Figure 6 is an enlarged partial top plan view showing the relation between the segments and the type carrier;

Figure 7 is an enlarged detail view, partly in elevation and partly in section, showing a modified construction of the connection for the anchorage end of the toggle;

Figure 8 is a detail plan view of the connection shown in Figure 7, and

Figure 9 is a view similar to Figure 3 but showing a modified form of connection between the toggle and the key lever.

As above stated, the invention is illustrated as embodied in the Royal standard machine, and there is shown the main frame A, the usual carriage B carrying a platen C, and the usual keyboard with the usual key levers D.

The frame A includes a front plate 1, a top plate 2, and a removable cover plate 3. These two plates are disposed in front of the platen C and the rear ends thereof terminate in spaced relation to said platen. Carried by the under side of the top plate 2 is a horizontally disposed arcuate segment 4 which is provided with a series of vertically disposed and radially extending slots 5 for receiving the upper or pivot ends of the type carriers or arms 6. An arcuate pivot rod 7

90

70

65

60

55

50

45

40

35

extends through suitable openings in the segment 4 and forms a pivot for all of the type carriers or arms 6. The pivot 7 is disposed in front of the platen C so as to permit the type carriers to normally hang vertically by gravity and to permit of said carriers being separately swung upwardly into a horizontal printing position with their free ends in front of the platen. Attached to the under face of the top plate 2 is a pad 8 which constitutes a stop for limiting the upward swinging movement of the carriers. An arcuate stop 9 is suitably supported by the main frame for limiting the downward movement 15 of the carriers.

The key levers D are preferably pivoted to a rod 10 which is located directly under the platen C. In order to move a given type carrier 6 upwardly to its printing position 20 upon the first part of the depression of the associated key levers D, however, I have provided a connection between the carrier and the lever which includes a toggle which is indicated generally at E. This toggle includes a long link 11 and a short link 12, said links being pivotally connected as at 13. The other end of the short link 12 is pivotally connected as at 14 to the type carrier or arm 6 at a point below the pivot 7 thereof when 25 the carrier is in its normal position. The anchorage end of the long link 11 is adapted to progressively vary after the type carrier has reached its printing position a distance determined by the depression of the 30 key lever. To this end a horizontally disposed arcuate segment 15 is attached to the main frame A and is located below and in rear of the segment 4. The segment 15, like the segment 4, is provided with a series of 35 vertically disposed and radially extending slots 16 in which the anchorage ends of the respective toggles E are adapted to be moved. A pin or rod 17 is mounted in the segment 15 and extends across the slots 16. The anchorage end of each long link 11 is provided 40 with a rearward extension 18 having an arcuate slot 19 formed thereon, said slot being curved on a radius having for its center the pivot 14. Thus, after the type carrier 6 has 45 been moved upwardly to its horizontal or printing position upon the first part of the depression of the associated key lever D, the toggle E, which has been straightened during such movement of the key lever, is then 50 capable of being swung about the pivot 14, whereby the anchorage end of said toggle will be moved forwardly and downwardly 55 to a position from that shown in Figure 3 to that shown in Figure 5. This swinging 60 movement of the toggle E has no effect on the movement of the carrier 6. In other words, the carrier 6 is held in its operative or horizontal position during the swinging movement of the toggle E during the latter 65 part of the depression of the key lever. In

the normal position of the parts, as shown in Figure 3, the rearward extension 18 of the toggle extends upwardly and rearwardly, and the major axis of the arcuate slot 19 extends in a downwardly and rearwardly direction. In order to actuate the toggle E and consequently the type carrier 6 during the first part of the depression of the associated key lever D, I have provided a link 20 which is adapted to be connected at its upper end 70 to any one of a plurality of holes 21 formed in the long link 11 adjacent the extension 18, the lower end of the link 20 being adapted to be connected to the key lever D through the medium of any one of a plurality of openings 22 formed in said lever. A coil spring 23 is associated with each type action, and the upper end of the spring is connected to an anchorage plate 24 fixed to the segment 15, and the lower end of said spring is connected 75 to an anchorage 25 which is fixed to the link 20. The longitudinal axis of the spring 23 is inclined downwardly and rearwardly and is disposed in substantial parallelism with the major axis of the slot 19 of the toggle E. The spring 23 therefore functions to yieldably retain the associated key lever D in its 80 normal position, and also to retain the type carrier 6 and the connections between the carrier and the key lever in their normal 85 positions.

Mounted on the free end of each type carrier or arm 6 is a type block F for sliding movements longitudinally of the arm. The type block is yieldably held against outward movement so that when the type arm is moved to its operative horizontal position the type will be spaced from the platen a distance sufficient to place one or more sheets of paper therebetween. Means are provided for positively moving the type block to print after the type arm has been moved to its horizontal printing position. This printing movement of the type block is accomplished through the medium of an impression member G which is moved through connections with all of the key levers during the latter part of the depression of any one key lever. The outer or free end of each type arm 6 is provided with a foot 26 which extends in a direction substantially at right angles to the longitudinal axis of the type arm. The type block F includes a holder 27 and a type plate 28^a which is attached to the holder by a screw 26^a or other suitable means. The holder 27 is of U-shaped construction and includes spaced side arms 28—28 and a connection portion 29. The inner faces of the side arms 28 are respectively formed with longitudinally extending guide grooves 30—30 which receive ribs 31—31 which extend laterally from the foot 26 of the type arm, said ribs 31 extending longitudinally of the type arm, or in a direction parallel to the major axis of said type arm. This rib 125

and groove connection 30, 31 between the type block F and the type arm 6 functions to permit the type block to be moved longitudinally of the type arm and also functions to retain the type block against movement transverse to the type arm. The connecting portion 29 of the type block is located in spaced relation to the inner end of the foot 26, and the type plate 28^a extends across the outer ends of the side arms 28-28 and forms a closure for said end. This type plate 28^a is adapted to normally lie against the outer end of the foot 26 of said type arm, and consequently the type block F is held by such engagement against further movement towards the pivot of the type arm. A coil spring 32 is disposed within the holder 28 between the connecting portion 29 thereof and the foot 26, and this spring serves to yieldably retain the type block against further or printing movement.

The impression member G is slidably mounted in a bore 33 formed in the cover plate 3. The bore 33 extends fore and aft of the machine and is centrally located relative to the series of type carriers 6. The impression member G is formed of a rod which extends forwardly from the rear end of the cover plate 3 to a point substantially above the segment 15. The impression member G is adapted to be reciprocated through the medium of a connection which is common to all of the key levers D. This connection includes a bell crank lever pivotally connected as at 38 to the upper end of a vertical link 39, the lower end of said link being pivotally connected as at 40 to a universal frame H which is fulcrumed on the main frame A through the medium of a cross rod 41. The universal frame H is disposed below and in spaced relation to the key levers D when said levers are in their normal positions. A spring 42 has one end connected to the universal frame H and the other end to an anchorage 45 fixed to the stop 9, and this spring functions to yieldably retain the universal frame H against downward movement under the influence of any one key lever. The universal frame H is provided with an upstanding arm 43 which is connected to the usual universal bar (not shown) which controls the movement of the carriage escapement mechanism. The bell crank lever 34 is pivoted at its anchor as at 44 to a support 45' which is adapted to be manually adjusted fore and aft of the machine, or, in other words, in a direction parallel to the reciprocatory movement of the impression member G. For this purpose the support 45' is mounted in an opening 46 formed in the front plate 1 of which machine frame A, and an adjusting screw 47 is carried by the support for cooperation with the plate 46 to retain the support 45' in any position of adjustment. By means of the adjustable sup-

port 45' the fulcrum of the bell crank lever 34 may be readily adjusted, and, as a result, the effective working position of the free or rear end of the impression member G may be varied. By means of this adjustment the extent of movement of the printing block may be correspondingly varied in order to meet practical requirements relative to different thicknesses or numbers of papers being fed around the platen C. In other words, when the support 45' is moved forwardly, the fulcrum 44 of the bell crank lever will be correspondingly moved forwardly, and, as a result, the path of reciprocation of the impression member G will be bodily moved rearwardly a corresponding amount. This will permit of an increased number of sheets to be fed around the platen between the platen and the type block. When it is desired to employ a minimum number of sheets, the support 45' is adjusted so as to move the same rearwardly and thereby correspondingly move the effective working position of the impression member G.

It will be desirable to reduce the amount of friction between the walls of the arcuate slot 19 and the pivot pin 17 of the toggle E, and to this end I have provided an anti-friction roller as shown in Figures 7 and 8. In these figures the arm E is provided with a forward extension 18 having a slightly enlarged arcuate slot 48 formed therein. The pivot pin or rod 17 is provided with an anti-friction roller 49 which rides in the slot 48, and this roller is provided with side flanges 50 which function to properly guide the anchorage end of the toggle E during its swinging movement.

In order to create a somewhat smoother type action, I may employ a secondary lever 51 in the link connection between the toggle E and the associated key lever D. There is of course one of the secondary levers 51 employed for each type action, and these secondary levers 51 are therefore pivoted at their front ends to a rod or pivot pin 52 which is supported in a horizontally disposed arcuate segment 53 carried by the main frame A, said levers 51 moving in vertically disposed and radially extending slots 54 formed in said segment 53. The rear end of each lever 51 is pivotally connected to the lower end of a link 54', the upper end of the link being pivotally connected to one of the openings 21 formed in the long link 11 of the toggle E. A second vertical link 55 is provided, and the upper end of this link is pivotally connected as at 56 to the secondary lever 51 at a point intermediate its ends, and the lower end of the link 55 is pivotally connected to one of the openings 22 in the associated key lever D.

In operation, assuming the parts to be in the position shown in Figure 3, it will be apparent that, upon the first part of the de-

pression of a predetermined key lever D, the link 20 will cause the toggle E to be first straightened and simultaneously the type carrier 6 swung to its horizontal printing position as shown in Figure 4.

In this position of the type carrier 6, the type block F is located directly in front of the impression member G, whereby, upon rearward movement of the member G, the type block will be directly engaged thereby and slid rearwardly along the type arm to print. During the latter part of the depression of said key lever, the universal frame H will be rocked thereby, and, through the medium of link 39, the bell crank lever 34 will be oscillated, and consequently the impression member G will be moved rearwardly to effect the printing operation by the type block, as previously described. During this latter part of the depression movement of the key lever, the toggle E will be swung on its pivot 14, the anchorage end of the toggle progressively varying downwardly to permit of the impression member G and the operating connections therefor being moved without straining the connections between the type carrier 6 and the key lever D. After a printing operation has been completed, the key lever D will return to its normal position by means of the spring 23, and simultaneously the type carrier 6 will swing downwardly to its normal position. At the same time the spring 42 will return the universal frame H to its normal position, and consequently the impression member G will likewise be returned to its normal position.

The type plate 28^a is provided with a centrally disposed attaching flange 28^b which is positioned between the side arms 28, 28 of the holder 27 and above the grooves 30 thereof, and is fixedly secured in such position by the screw 26^b.

The end of the plunger G is provided with a reduced extension g, which during printing movement will engage in a correspondingly sized opening formed in the connecting portion 29 of the holder F and thereby guide that portion of the holder in a straight line and also act as a lock to hold the type bar upwardly against the pad 8 to insure accurate alignment of the type carrier. In other words, the reduced end portion g of the plunger cooperates with the type bar to hold the same in perfect vertical and lateral alignment.

What I claim is:

1. A type action comprising, in combination, a movable type arm having a type block mounted for relative movements at one end, a key lever, and means actuated by the key lever for first swinging the type arm to printing position and thereafter moving said type block to print, said means including a toggle having one end pivoted to the type arm and having its anchorage end progressively vary-

ing after the arm has reached its printing position a distance determined by the depression of the key lever, and a connection between the toggle and the key lever.

2. A type action comprising in combination, a type arm pivoted at one end and having a type block mounted for relative movements at the other end, a key lever, and means actuated by the key lever for first swinging the type arm to printing position and thereafter moving said type block to print, said means including a toggle embodying relatively short and long links, the free end of the short link being pivotally connected to the type arm, and a link connecting the long link of the toggle with the key lever.

3. A type action comprising in combination, a movable type arm having a type block mounted for relative movements at one end, a key lever, and means actuated by the key lever for first swinging the type arm to printing position and thereafter moving said type block to print, said means including a toggle embodying relatively short and long links, the free end of the short link being pivotally connected to the type arm, the anchorage end of the long link progressively varying after the arm has reached its printing position a distance determined by the depression of the key lever, and a connection between the long link of the toggle and the key lever.

4. A type action comprising in combination, a movable type arm having a type block mounted for relative movements at one end, a key lever, and means actuated by the key lever for first swinging the type arm to printing position and thereafter moving said type block to print, said means including a toggle having one end pivoted to the type arm and having its anchorage end progressively varying after the arm has reached its printing position a distance determined by the depression of the key lever, a spring for yieldably retaining the anchorage end of the toggle against said progressive varying, and a connection between the toggle and the key lever.

5. A type action comprising in combination, a movable type arm having a type block mounted for relative movements at one end, a key lever, and means actuated by the key lever for first swinging the type arm to printing position and thereafter moving said type block to print, said means including a toggle embodying relatively short and long links, the free end of the short link being pivotally connected to the type arm, the anchorage end of the long link progressively varying after the arm has reached its printing position a distance determined by the depression of the key lever, a spring for yieldably retaining the anchorage end of the toggle against said progressive varying, and a link connecting the long link of the toggle with the key lever.

6. A type action comprising in combination, a movable type arm having a type block

mounted for relative movements at one end, a key lever, and means actuated by the key lever for first swinging the type arm to printing position and thereafter moving said type 5 block to print, said means including a toggle embodying relatively short and long links, the free end of the short link being pivotally connected to the type arm, the anchorage end of the long link progressively varying after the arm has reached its printing position a 10 distance determined by the depression of the key lever, a spring for yieldably retaining the anchorage end of the toggle against said progressive varying, and a connection between the long link of the toggle and the key 15 lever.

7. A type action comprising in combination, a movable type arm having a type block mounted for relative movements at one end, 20 a key lever, and means actuated by the key lever for first swinging the type arm to printing position and thereafter moving said type block to print, said means including a toggle having one end pivoted to the type arm and 25 having its anchorage end mounted to swing in an arc concentric with the pivot connecting the toggle and the type arm a distance determined by the depression of the key lever, and a connection between the toggle and the 30 key lever.

8. A type action comprising in combination, a movable type arm having a type block mounted for relative movements at one end, a key lever, and means actuated by the key 35 lever for first swinging the type arm to printing position and thereafter moving said type block to print, said means including a toggle having one end pivoted to the type arm and having its anchorage end mounted to swing 40 in an arc concentric with the pivot connecting the toggle and the type arm a distance determined by the depression of the key lever, a spring for yieldably retaining the anchorage end of the toggle against swinging, and 45 a connection between the toggle and the key lever.

9. A type action comprising in combination, a movable type arm having a type block mounted for relative movements at one end, 50 a key lever, and means actuated by the key lever for first swinging the type arm to printing position and thereafter moving said type block to print, said means including a toggle embodying relatively short and long links, 55 the free end of the short link being pivotally connected to the type arm, the anchorage end of the long link including a pin and slot connection for permitting the toggle to swing in an arc concentric with the pivot connect- 60 ing the short link and the type arm a distance determined by the depression of the key lever, and a link connecting the long link of the toggle with the key lever.

10. A type action comprising in combina- 65 tion, a movable type arm having a type block

mounted for relative movements at one end, a key lever, and means actuated by the key lever for first swinging the type arm to printing position and thereafter moving said type block to print, said means including a toggle embodying relatively short and long links, the free end of the short link being pivotally connected to the type arm, the anchorage end of the long link including a pin and slot connection for permitting the toggle to swing in an arc concentric with the pivot connecting the short link and the type arm a distance determined by the depression of the key lever, a spring for yieldably retaining the anchorage end of the toggle against movement, and a link connecting the long link of the toggle with the key lever. 70 80

11. A type action comprising in combination, a movable type arm having a type block mounted for relative movements at one end, 85 a key lever, and means actuated by the key lever for first swinging the type arm to printing position and thereafter moving said type block to print, said means including a toggle having one end pivoted to the type arm and having its anchorage end progressively varying after the arm has reached its printing position a distance determined by the depression of the key lever, a spring for yieldably retaining the anchorage end of the toggle 90 against said progressive varying, the spring being expansible in a direction substantially parallel with the direction of movement of the anchorage end of the toggle, and a connection between the toggle and the key lever. 95 100

12. A type action comprising in combination, a movable type arm having a type block mounted for relative movements at one end, a key lever, and means actuated by the key lever for first swinging the type arm to printing position and thereafter moving said type block to print, said means including a toggle having one end pivoted to the type arm and having its anchorage end mounted to swing 105 in an arc concentric with the pivot connecting the toggle and the type arm a distance determined by the depression of the key lever, a spring for yieldably retaining the anchorage end of the toggle against swinging, the spring being expansible in a direction 110 substantially parallel to the path of swinging movement of the anchorage end of the toggle, and a connection between the toggle and the key lever. 115

13. A type action comprising in combination, a movable type arm having a type block mounted for relative movements at one end, a key lever, and means actuated by the key lever for first swinging the type arm to printing position and thereafter moving said type block to print, said means including a toggle embodying relatively short and long links, the free end of the short link being pivotally connected to the type arm, the anchorage end of the long link including a pin and slot con- 120 125 130

- nection for permitting the toggle to swing in an arc concentric with the pivot connecting the short link and the type arm a distance determined by the depression of the key lever, the spring being expansible in a direction substantially parallel to the major axis of the slot of said connection, and a link connecting the long link of the toggle with the key lever.
14. A type action comprising in combination a movable type arm having a type block mounted for relative movement at one end, a key lever, means for moving the type arm to printing position during the first part of the depression of the key lever, and means including a movable impression member, and means for moving the impression member to move the type block during the latter part of the depression of the key lever and while the type arm is in printing position, said impression moving means including a bell crank lever having one arm directly connected to the impression member, a frame movably mounted under the key lever and normally spaced therefrom, and a connection between the other arm of the bell crank lever and said movable frame.
15. A type action comprising in combination a movable type arm having a type block mounted for relative movement at one end, a key lever, means for moving the type arm to printing position during the first part of the depression of the key lever, and means including a movable impression member, and means for moving the impression member to move the type block during the latter part of the depression of the key lever and while the type arm is in printing position, said impression moving means including a bell crank lever having one arm directly connected to the impression member, a frame movably mounted under the key lever and normally spaced therefrom, and a connection between the other arm of the bell crank lever and said movable frame.
16. A type action comprising in combination, a movable type arm having a type block mounted for relative movement at one end, a key lever, means for moving the type arm to printing position during the first part of the depression of the key lever, and means including a movable impression member, and a bell crank lever connected thereto and to the key lever for moving the impression member to move the type block during the latter part of the depression of the key lever and while the type arm is in printing position, and means for adjusting the fulcrum of the bell crank lever in a direction parallel to the path of movement of the impression member to vary the effective working position of said member.
17. In a type action, a movable type arm having a foot at one end extending in a plane at right angles to the longitudinal axis of the arm, and a U-shaped type block mounted on said foot to slide longitudinally of the arm, said block including side arms and a connecting portion, the side arms being disposed on opposite sides of the foot and the connecting portion being disposed adjacent the inner end of the foot, a type plate attached to the block and extending across the outer ends thereof for direct contact with the outer end of the foot to limit the inward movement of the type block, and cooperating means between the foot and the block for guiding the block longitudinally of the arm.
18. In a type action, a movable type arm having a foot at one end extending in a plane at right angles to the longitudinal axis of the arm, and a U-shaped type block mounted on said foot to slide longitudinally of the arm, said block including side arms and a connecting portion, the side arms being disposed on opposite sides of the foot and the connecting portion being disposed adjacent the inner end of the foot, a type plate attached to the block and extending across the outer ends thereof for direct contact with the outer end of the foot to limit the inward movement of the type block, a spring interposed between the connecting portion of the block and the foot for yieldably retaining the block against outward movement relative to the type arm, and cooperating means between the foot and the block for guiding the block longitudinally of the arm.
19. In a typewriting machine the combination with a platen of a plurality of type arms each pivoted to normally hang downwardly in front of the platen and adapted to be swung upwardly to an operative horizontal printing position with its free end in front of the platen, a movable type block mounted on the free end of each type arm, a plurality of key levers, operative connections between the respective key levers and type arms for moving a predetermined arm to its operative horizontal printing position during the first portion of the depression of its associated key lever, each of said connections including a toggle having one end pivoted to the type arm and having its anchorage end progressively varying after the arm has reached its printing position a distance determined by the depression of the key lever, and a connection between the toggle and the key lever, and means operated by the same key lever during the latter part of its depression and while said arm is in its operative position to move the type block to print.
20. In a typewriting machine the combination with a platen of a plurality of type arms each pivoted to normally hang down-

wardly in front of the platen and adapted to be swung upwardly to an operative horizontal printing position with its free end in front of the platen, a movable type block mounted on the free end of each type arm, a plurality of key levers, operative connections between the respective key levers and type arms for moving a predetermined arm to its operative horizontal printing position during the first portion of the depression of its associated key lever, each of said connections including a toggle having one end pivoted to the type arm and having its anchorage end progressively varying after the arm has reached its printing position a distance determined by the depression of the key lever, and a connection between the toggle and the key lever, and means operated by the same key lever during the latter part of its depression and while the arm is in its operative printing position to move the type block to print, said means including a reciprocatory impression member for moving the type block to print, a universal frame cooperating with said key lever, and operative connections between the universal frame and said impression member.

21. In a typewriting machine the combination with a platen of a plurality of type arms each pivoted to normally hang downwardly in front of the platen and adapted to be swung upwardly to an operative horizontal printing position with its free end in front of the platen, a movable type block mounted on the free end of each type arm, a plurality of key levers, operative connections between the respective key levers and type arms for moving a predetermined arm to its operative horizontal printing position during the first portion of the depression of its associated key lever, each of said connections including a toggle having one end pivoted to the type arm and having its anchorage end progressively varied after the arm has reached its printing position a distance determined by the depression of the key lever, and a connection between the toggle and the key lever, and means operated by the same key lever during the latter part of its depression and while said arm is in its operative position to move the type block to print, said means including a reciprocatory impression member for moving the type block to print, a bell crank lever pivotally connected to the impression member, and an operative connection between the bell crank lever and the universal frame, and means for bodily adjusting the bell crank lever to vary the effective working position of the impression member.

plurality of key levers, operative connections between the respective key levers and type arms for moving a predetermined arm to its operative horizontal printing position during the first portion of the depression of its associated key lever, each of said connections including a toggle having one end pivoted to the type arm and having its anchorage end progressively varying after the arm has reached its printing position a distance determined by the depression of the key lever, and a connection between the toggle and the key lever, means operated by the same key lever during the latter part of its depression and while said arm is in its operative position to move the type block to print, said means including a reciprocatory impression member for moving the type block to print, a bell crank lever pivotally connected to the impression member, and an operative connection between the bell crank lever and the universal frame, and means for bodily adjusting the bell crank lever to vary the effective working position of the impression member.

In testimony whereof, I have hereunto subscribed my name.

EDWARD B. HESS.
